UNITED STATES PATENT OFFICE.

ANDREW J. SANFORD, OF NEWARK, OHIO, ASSIGNOR TO A. H. HEISEY & CO., OF NEWARK, OHIO.

DESIGN FOR A PITCHER.

52,675.

Specification for Design.

Patented Nov. 12, 1918.

Application filed May 22, 1917. Serial No. 170,294. Term of patent 14 years.

To all whom it may concern:

Be it known that I, ANDREW J. SANFORD, a citizen of the United States, residing at Newark, Ohio, have invented a new, original, and ornamental Design for a Pitcher, of which the following is a specification, reference being had to the drawing, which is a side elevation of a pitcher embodying the invention.

The pitcher is characterized by an accentuated flared bottom, and a still more ac-

centuated flared handle, the thickness of the lower part of which is more than quadruple the thickness of the upper part. The assemble of this handle gives a bizarre ornamental ear-lobe effect grafted upon the trunk.

I claim:

The ornamental design for a pitcher as shown.

ANDREW J. SANFORD.
